UNITED STATES PATENT OFFICE.

ARTHUR L. ARCHAMBEAULT, OF STOCKTON, CALIFORNIA.

WINKER-STAY FASTENER AND HOLDER.

SPECIFICATION forming part of Letters Patent No. 696,533, dated April 1, 1902.
Application filed September 26, 1901. Serial No. 76,663. (No model.)

To all whom it may concern:

Be it known that I, ARTHUR L. ARCHAMBEAULT, a citizen of the United States, residing at Stockton, in the county of San Joaquin 5 and State of California, have invented certain new and useful Improvements in Winker-Stay Fasteners and Holders; and I do declare the following to be a full, clear, and exact description of the invention, such as will enable others skilled in the art to which it appertains 10 to make and use the same.

This invention relates to improvements in winker-stay fasteners for attaching winker-stays to bridle-blinds.

15 The object of the invention is to do away with the practice of sewing the stay to the blind and to provide a mechanical fastening which will effectually prevent the loosening or tearing away of the stay from the blind 20 under wear or strain or under the pull exerted when the horse rubs his head against a surface.

With this and other objects in view the invention consists of certain novel features of 25 construction, combination, and arrangement of parts, as will be hereinafter more fully described, and particularly pointed out in the appended claims.

In the accompanying drawings, Figure 1 is 30 an elevational view of a blind and winker-stay equipped with my invention. Fig. 2 is a vertical longitudinal section taken through the blind, winker-stay, and fastener. Fig. 3 is a detail view of the fastener or holder detached, 35 and Fig. 4 is a view showing a modification in which the fastener is formed as part of the reinforcing-plate of the blind.

Referring now more particularly to the drawings, the numeral 1 represents a bridle- 40 blind formed in the usual manner of two side pieces or plies 2 and 3 of leather and an interposed metallic reinforcing-plate 4, which maintains the blind in proper shape, and 5 represents the winker-stay.

45 In carrying my invention into practice I provide a metallic holding or fastening plate 6, provided at its upper end with a guide-slot 7 and having its said upper end bent downwardly to form an embracing hook 8. The body 50 portion of the plate is slotted and a portion of the metal displaced to form an outwardly and downwardly projecting tongue 9. In apply-

ing the fastening to the blind to attach the winker-stay thereto the plate 6 is located against the outer surface of one of the leather plies 2 or 3, being shown in the present instance as arranged to bear against the outer surface of the ply 3, and its tongue 9 is passed through perforations in said ply 2 and through corresponding perforations in the reinforcing-plate 4 and connecting end of the stay 5 and bent downward and clenched against said stay to hold the parts rigidly united. The upper end of the plate 6 stands in line with or a little above the upper edges of the plies 65 2 and 3 and the hook 8 bent over toward the ply 2, so that the slot 7 comes on a line between the said ply 2 and the reinforcing-plate 4. The connecting end of the stay 5 passes downwardly through the slot 7 in the plate 6 70 and lies between the ply 2 and reinforcing-plate 4 and is connected with the tongue 9 in the manner heretofore described, so as to be firmly clamped in position and held securely against withdrawal. The hook 8 after the 75 stay has been passed through the slot 7 is brought over beyond the outer surface of the leather ply 2 and bent downwardly, so as to bear against the same, whereby the upper edges of the plies 2 and 3 are held between 80 the plate 6 and hook 8 and clamped against the interposed metallic reinforcing-plate 4. By this construction it will be seen that a simple, safe, and secure fastening is provided, which holds the parts in intimate engagement 85 and prevents loosening or detachment of the stay 5 against all ordinary pulling strains. In the ordinary construction of harness-blinds the end of the stay 5 is connected to the blind by stitching it to the leather portions of the 90 blind, rendering the fastening insecure and adapted to loosen or pull out under ordinary service, and especially when the horse tosses his head or rubs the blind against a surface, setting up a pulling strain, under which the 95 stitches are liable to loosen and the end of the stay to pull out or become torn away from the blind. My invention obviates this objection in a simple and effective manner and holds the stay secure to the blind in a much firmer 100 and surer manner than is attainable by the use of stitches.

In the modification of the invention shown in Fig. 4 the holder or fastener is formed as

an integral part of the metallic reinforcing-plate 4 by providing said plate with an offset portion 10, having the guide-slot 7 and adapted to be bent down to form the hook 8 and 5 by slitting and displacing a portion of the metal of the plate below said offset portion to form the tongue 9. When this embodiment of the invention is employed for securing the stay, it will of course be understood 10 that the hook 8 is bent over to engage the leather ply 2, while the winker-stay passes downward through the slot 7 and lies between said ply and the reinforcing-plate, as hereinbefore described.

15 From the foregoing description, taken in connection with the accompanying drawings, the construction, mode of operation, and advantages of the invention will be readily understood without a further extended description, and it will be seen that the invention 20 provides a fastening which will hold the winker-stay firmly against casual displacement.

Changes in the form, proportion, and minor 25 details of construction may be made within the scope of the invention without departing from the spirit or sacrificing any of the advantages thereof.

Having thus fully described my invention, 30 what I claim as new, and desire to secure by Letters Patent, is—

1. In a winker-stay fastening, and in combination with a winker-stay having a slit

formed therein, a plate formed with an integral tongue adapted to be passed through said slit and clenched to hold said stay in place, and bent at its upper end to form an integral hook slotted for the passage of the stay, substantially as described. 35

2. In a winker-stay fastening, the combination with a bridle-blind comprising leather plies and a reinforcing-plate inserted between said plies; of a winker-stay having its connected end passed downwardly between one of the plies and said reinforcing-plate and 40 slitted, and a fastener consisting of a metallic plate bearing against one of the plies and provided with an integral tongue projecting through said ply, the connecting-plate and the slit in the stay and clenched to hold said stay in position and further provided at its upper end with an integral hook having a guide-slot through which the stay projects, said hook being bent over the upper edges of the plies and reinforcing-plate and down 45 against the surface of the ply opposite that against which it bears for clamping the parts together, substantially as and for the purpose set forth. 50

In testimony whereof I have hereunto set 55 my hand in presence of two subscribing witnesses.

ARTHUR L. ARCHAMBEAULT.
